UNITED STATES PATENT OFFICE.

JOHN R. BEYNON, OF WATERTOWN, WISCONSIN, ASSIGNOR OF ONE-HALF
TO JAMES B. MURPHY, OF SAME PLACE.

ROLLER-MILL.

SPECIFICATION forming part of Letters Patent No. 394,814, dated December 18, 1888.

Application filed March 31, 1888. Serial No. 269,112. (No model.)

To all whom it may concern:

Be it known that I, JOHN R. BEYNON, of Watertown, in the county of Jefferson, and in the State of Wisconsin, have invented certain new and useful Improvements in Roller-Mills; and I do hereby declare that the following is a full, clear, and exact description thereof.

My invention relates to roller-mills; and it consists in certain peculiarities of construction and combination of parts, to be herein-after described with reference to the accompanying drawings and subsequently claimed, whereby the yielding roller in such mills may be readily and evenly adjusted throughout its entire length.

In the drawings, Figure 1 represents a side elevation, partly in section, of a portion of a roller-mill having my invention applied thereto; and Fig. 2 is an end view of the same, partly broken away and in section on line 2 2, Fig. 1. Figs. 3, 4, and 5, are detail views, the latter being a horizontal section taken on line 5 5 of Fig. 3.

Referring by letter to the drawings, A represents a portion of the frame-work of a roller-mill, B the stationary roller, and C the adjustable yielding roller. The journal-boxes of the stationary roller are each provided with a screw-threaded socket or opening, D, that receives the correspondingly-shaped end of an adjusting-rod, E, that is loose in an opening in the adjacent journal-box F of the adjustable yielding roller C, the movement of this latter roller being limited in a forward direction by means of a collar, G, on each adjusting-rod and in a rearward direction by a spiral spring, H, that surrounds each of these adjusting-rods between the journal-box F thereon and the rear portion of the frame-work A, in which said rods have a bearing, I, as illustrated by Fig. 1. Fast on the rear end of each adjusting-rod E is a worm-wheel, J, that meshes with a worm, K, on a spindle, L, the latter having its bearings in a hanger or casing, M, that is preferably made in two sections hinged together and fitted on the hub of said worm-wheel. The casing serves to protect the worm-gear from the dust and dirt, and the sections comprising said casing are

held in their closed position by a pin, N, that passes through ears O, depending from the top of said sections, the hinge being similarly constructed and lettered.

The inner end of each spindle L fits into a 55 socket, P, in the adjacent end of a handle, Q, and set-screws R serve to rigidly connect the spindles with said handle, the sockets in the latter being of sufficient depth to permit an adjustment to suit mills of different widths. 60

By turning the handle Q the worm-gear connection J K with the adjusting-rods E is actuated to move the roller C to or from the stationary roller B, and, as both ends of the former roller are acted upon at the same time, 65 the adjustment is equal throughout its length.

As best illustrated by Figs. 3 and 5, I prefer to elongate the bearings S for the worm-spindles L in order to better adapt my device to mills that have the journal-boxes of the adjustable yielding-roller C screw-threaded on the rods E and the journal-boxes for the stationary roller B loose on said rod, this construction being just the reverse of that shown by Fig. 1. 70

The advantage of the construction just described lies in the fact that in case any hard infrangible material should get between the rollers on either side of the center the handle Q and the worm-spindles connected thereto would be free to assume the same angle as the displaced roller; or, in other words, would remain parallel with said roller, thereby preventing any binding of said worm-spindles or kinking of the adjusting-rods. 75

In order to better insure the parallel movement of the yielding roller and the adjusting mechanism, I prefer to depress the sides of the sections that compose the casings M as shown by Figs. 3 and 5, so as to obtain points 80 T, that have a bearing on the worm-spindles L, to keep the latter in line with the centers of the worm-wheels J, the depressions gradually receding from said bearing-points toward the ends of said casings. 85

My device is applicable to any of the well-known styles of roller-mills, but as the arrangement of the springs for holding the yielding roller in its adjusted position and the construction by which the adjustment is effected 90 95 100

are so varied I have shown only one style of mill for the purpose of illustrating the application of my device; and it will be understood that I do not limit myself to any particular 5 roller-mill, nor the arrangement of devices whereby the yielding roller therein may be adjusted to or from the stationary roller, it being obvious that in some mills where my 10 worm-wheels take the places of the tension-nuts for the springs H said worm-wheels necessarily move on the adjusting-rods E, instead of having a movement therewith when the positive adjustment is effected. Furthermore, I do not wish to be understood as limiting myself to the worm-gear connection 15 between the adjusting-rods and spindles L, it being obvious that a bevel or other suitable gear may be employed for the same purpose.

Having thus fully described my invention, 20 what I claim as new, and desire to secure by Letters Patent, is—

1. In a roller-mill, the combination, with the yielding roller and its adjusting- rods, of a wheel fast on each adjusting- rod, a hanger 25 suspended from the hub of each wheel and provided with an elongated bearing, and a handle journaled in the bearings and geared to said wheels, substantially as set forth.

2. In a roller-mill, the combination, with the 30 yielding roller and its adjusting- rods, of a wheel fast on each adjusting- rod, a hanger suspended from the hub of each wheel, opposing spindles journaled in the hangers and geared to said wheels, and a handle detachably connected at its ends to the spindles, substantially as and for the purpose set forth.

3. In a roller-mill, the combination, with the

yielding roller and its adjusting- rods, of a 40 wheel fast on each adjusting-rod, a bearing suspended from the hub of each wheel, opposing spindles journaled in the bearings and geared to said wheels, and a handle connected to the spindles and adjustable in length, substantially as set forth.

4. In a roller-mill, the combination, with the 45 yielding roller and its adjusting- rods, of a wheel arranged on each adjusting-rod, a casing made in two sections hinged together and fitted to the hub of each wheel, a spindle journaled in each casing and geared to the wheel 50 incased thereby, and a handle uniting the opposing spindles, substantially as and for the purpose set forth.

5. In a roller-mill, the combination, with the yielding roller and its adjusting- rods, of a 55 wheel arranged on each adjusting-rod, a casing fitted to the hub of each wheel and having its sides depressed to form opposing bearing-points and its ends provided with elongated 60 bearings, a spindle arranged in the elongated bearings of each casing to impinge against said points, whereby the spindle is kept in line with the center of the adjacent wheel, a gear-connection established between said spindle and wheel, and a handle uniting the 65 opposing spindles, substantially as set forth.

In testimony that I claim the foregoing I have hereunto set my hand, at Milwaukee, in the county of Milwaukee and State of Wisconsin, in the presence of two witnesses.

JOHN R. BEYNON.
